UNITED STATES PATENT OFFICE.

ARTHUR A. KEMP, OF LORETTA, OKLAHOMA TERRITORY.

FINGER-GUARD FOR REVOLVERS.

SPECIFICATION forming part of Letters Patent No. 694,969, dated March 11, 1902.

Application filed November 9, 1900. Serial No. 35,968. (No model.)

To all whom it may concern:

Be it known that I, ARTHUR A. KEMP, a citizen of the United States, residing at Loretta, in the county of Beaver and Territory of Oklahoma, have invented a new and useful Attachment for Firearms, of which the following is a specification.

This invention relates to firearms in general, and more particularly to the class of revolvers wherein a cylinder is used for holding a number of cartridges, the object of the invention being to provide an attachment which will be so placed and constructed as to have a number of distinct uses.

15 In that class of revolvers known as the "Colt's" revolver the cylinder is rotatably mounted in a frame, the back end of the frame being hemispherical in form to cover the rear end of the cylinder and prevent any backward discharge from the cartridges. The cartridge-shells after having been discharged are ejected by means of a reciprocating rammer mounted below the barrel and at one side, and to permit discharge of the shells or ejection 20 of the shells a portion of the back of the frame is formed removable and is carried by an arm which is pivoted in a recess in the rear wall of the chamber in which the cylinder is disposed. When the shells are to be ejected, 25 this movable portion is swung outwardly from behind the cylinder, and when new cartridges have been inserted through the space thus left open the movable section is swung back into place, and one of the functions performed 30 by the present invention is to facilitate the swinging of this movable section into and out of its closed position and also to hold the movable section positively against outward swinging movement when the weapon is discharged. Furthermore, in a revolver there is a liability of clippings and gases to be discharged through the seam between the front end of the cylinder and the adjacent face of the frame, and the present attachment acts 35 to guard or protect the index-finger, which is usually held along the cylinder and with its outer end across this seam.

An additional object of the invention is to provide a simple means for preventing the revolver from slipping through the belt.

These several functions are all obtained by the formation and arrangement of the single simple attachment.

In the drawings forming a portion of this specification, and in which like numerals of reference indicate similar parts in the several views, Figure 1 is a perspective view showing the use of the attachment as a finger-guard. Fig. 2 is a perspective view showing the use of the attachment for preventing the revolver 55 from slipping through the belt of the user. Fig. 3 is a transverse section taken through the revolver just in the rear of the cylinder. Fig. 4 is a section taken through the base of the attachment and through the pivoted block 65 to which it is attached.

Referring now to the drawings, there is shown a revolver of the Colt type, including a barrel 5, a frame 6, and a cylinder 7, rotatably mounted in the usual manner, the rear 70 end of the frame directly behind the cylinder being formed to cover the entire rear end of the cylinder and this rear end of the frame having a movable section in the form of a block 8, which when in place completes the closure of 75 the rear end of the cylinder and when removed from place exposes the chambers of the cylinder successively as the cylinder is rotated. The block 8, as shown in Fig. 3 of the drawings, is carried by an arm 9, which is pivoted 80 in a recess 10 in the rear face of the frame and when moved upon its pivot carries the block into and out of its closed position, it being understood that the block when in position prevents, in connection with the remainder 85 of the rear of the frame, backward discharge, while when in its open position it permits the shells to be successively ejected in the well-known manner. The attachment of the present invention is carried by this block 8, which 90 latter, with its arm, lies flush with the face of the frame when in closed position. The attachment consists of a finger 15, preferably of spring-steel, the body portion of which is given a compound curve. The finger is of 95 flat or cross-sectionally curved metal, as preferred, and the rear end thereof is bent to lie at right angles to the common chord of the curvature of the finger, and this laterally-bent portion is cross-sectionally formed into a dove- 100

1, as shown in Fig. 4 of the drawings, to engage a dovetail recess 16, formed in the front face of the block 8, this rear end of the finger 15 engaged with the recess lying flush with the face of the block. To secure a tight fit the end of the finger in the recess of the block, the said end is slightly tapered, as shown, and to prevent accidental removal hereof a retaining-screw 17 is passed through the laterally-bent end 15' of the finger and into the block 8. As shown in Figs. 1 and 2 of the drawings, the finger 15 lies spaced slightly from the periphery of the cylinder of the revolver to permit the latter to turn freely and, furthermore, to permit the revolver to be slipped on the inside of a belt while the finger is passed down over the outside of the belt to rest with the inturned end 15' against the upper edge of the belt and prevent the revolver from slipping down and entirely through the belt, as shown in Fig. 2. Fig. 1 shows the finger 15 lying with the chord of its curvature parallel with the barrel of the revolver, so that when the revolver is to be fired the index-finger may be laid along this finger 15 and will fit snugly thereagainst not only to hold the revolver securely, but primarily to insure proper aim. Should the block 8 stick in its closed position, the finger 15 affords a means for readily swinging the block from its place instead of necessitating insertion of the thumb of the user behind the block, the fin-

ger 15 giving a much greater leverage, as will be understood.

It will of course be understood that in practice modifications of the specific construction shown may be made and that any suitable materials and proportions may be used for the various parts without departing from the spirit of the invention.

40

What is claimed is—

A firearm including as one of its elements, a movable loading-gate having in its forward face a dovetail groove 16, and a combined handle, finger-guard and hanger 15 consisting of a curved plate extended forward beyond the juncture of the cylinder and barrel and at its rear end being curved inwardly to form shoulders to rest against the outer edge of the gate, said rear end being bent transversely to the line of the main body of the device and having a narrowed tapering end 15' adapted to said dovetail groove, and a retaining-screw passing through said plate into the body of the gate, substantially as and for the purpose set forth.

In testimony that I claim the foregoing as my own I have hereto affixed my signature in the presence of two witnesses.

ARTHUR A. KEMP.
